ANODE

Howard H. Blouch, Cleveland, Ohio, assignor, by
mesne assignments, to E. I. du Pont de Nemours
& Company, Wilmington, Del., a corporation of
Delaware

Application April 7, 1934, Serial No. 719,453

5 Claims. (Cl. 204—4)

This invention relates to anodes for use in electroplating and is particularly directed to anodes cast upon a support, or spine, which is provided with means along its length providing surfaces upon which the anode material may rest and about which the anode material may cling.

In the manufacture of anodes it has been the practice to cast the anode material around a spine which is inert to the plating bath, the spine being provided with a hook by means of which the anode may be suspended. This method of construction is not entirely satisfactory, since uneven anode corrosion removes the active material from one side or another and the remainder falls from the spine, frequently damaging mechanical equipment. The anode material which becomes detached from the spine is no longer available for its intended use in plating, and the life of the anode is greatly decreased.

It is an object of my invention to improve the bond between the inert material of the spine and the active anode material cast around it, so that the anode material will remain on the spine until it is almost entirely utilized, thereby effecting a great economy of anode material. I accomplish my purpose by modifying the spine so that surfaces in planes other than those of the spine faces are provided to anchor the anode material.

In the drawing:

Figure 1 illustrates an anode provided with a spine modified according to my invention.

Figures 2—8, inclusive, show portions of modified spines embodying my invention.

In Figure 1 there is illustrated a curved anode 1 cast upon a spine 2. The spine is provided with a hook 4 by means of which the anode may be suspended in an electroplating bath. The anode material is that which one desires to electrodeposit and may be, for example, zinc, cadmium, or tin. The spine is made of any material customarily used in this relation, and is preferably iron or steel. The spine is provided with holes 3 approximately elliptical in shape which provide surfaces in planes other than those of the spine faces. The anode material, when cast on the spine, fills the holes 3 and firmly anchors the anode to the spine. Even if the corrosion of the anode occurs more rapidly on one side than on the other, the remaining anode material does not fall off, but is held securely by the spine. Obviously, the holes may be widely varied as to size and shape without departing from the spirit of my invention.

In the modification of Figure 2 the spine 2, of which only a portion is shown, is provided with

struck-out, upwardly directed hooks 5, adjacent hooks being on opposite sides of the spine.

In Figure 3 the hooks 5 are all on the same side of the spine. This modification is best applied to a curved spine, the hooks being bent away from the center of curvature.

In Figure 4 the hooks 6 are punched from the edges of the spine 2 instead of from the center as in Figures 2 and 3. The hooks 6 are bent so that adjacent hooks are on the opposite sides.

The modification of Figure 5 is similar to that of Figure 4, except that the hooks 6 are all bent in the same direction.

Instead of having the hooks integral with the spine, I may secure them in place as by welding. In Figure 6 the spine 2 is provided with hooks 7. The hooks 7 are shown as round, upwardly directed pins.

It is apparent that the hooks struck from, or secured to, the spine may be varied as to size and shape without departing from the spirit of my invention. The hooks may, obviously, extend from the spine at any desired angle, though in general I prefer upwardly directed hooks. Figure 7 illustrates a modification wherein a spine 2 is provided with struck-out hooks 8. The hooks 8, instead of being upwardly directed, are bent downwardly. The spine of Figure 7 operates very satisfactorily.

The spine may, of course, be of any desired cross section. In Figure 8 there is seen a portion of a spine 9 which is round in cross section. The hooks used are short pieces of wire 10 which are wrapped partly around the spine and welded in place.

My improved spines can be used with curved anodes, such as that of Figure 1, or with straight anodes. It is also noted that preliminary to casting the anode materials upon the spines of my invention, I find it advantageous to coat the spines with some of the anode material. The spines may be preliminarily coated by such plating processes as electrodeposition, dipping the spine into a bath of the anode material in molten condition, etc. This preliminary coating of anode material increases the adhesion between the spine and the anode cast upon it.

I claim:

1. An anode of the type described comprising a spine with anode material cast thereupon, the spine being provided with struck-out hooks.

2. An anode of the type described comprising a spine with anode material cast thereon, the spine being provided with struck-out hooks, part of the

hooks extending in one direction, and the remaining hooks extending in other directions.

3. An elongated, imperforate, soluble anode of the type wherein the anode material is dissolved in use, the soluble anode material being cast upon a spine of insoluble material which extends substantially the whole length of the anode, and the spine being provided with struck-out hooks.

4. An elongated, imperforate, soluble anode of the type wherein the anode material is dissolved in use, the soluble anode material being cast upon a spine of insoluble material which extends substantially the whole length of the anode, and the

spine being provided with surfaces in a plane other than those of the spine faces whereby in use the anode material is retained on the spine until almost entirely utilized.

5. An elongated, imperforate, soluble anode of the type wherein the anode material is dissolved in use, the soluble anode material being cast upon a spine of insoluble material which extends substantially the whole length of the anode, and the spine being provided with projecting hooks 10 whereby in use the anode material is retained on the spine until almost entirely utilized.

HOWARD H. BLOUCH.
